UNITED STATES PATENT OFFICE.

CARL W. BAUMGARDNER, OF TIFFIN, OHIO.

CONCRETE BURIAL-VAULT MOLD.

1,247,784.

Specification of Letters Patent. Patented Nov. 27, 1917.

Application filed August 2, 1917. Serial No. 184,121.

To all whom it may concern:

Be it known that I, CARL W. BAUMGARDNER, a citizen of the United States, residing at Tiffin, in the county of Seneca and State 5 of Ohio, have invented certain new and useful Improvements in Concrete Burial-Vault Molds; and I do declare the following to be a full, clear, and exact description of the invention, such as will enable others skilled 10 in the art to which it appertains to make and use the same.

My invention relates to that class of molds adapted for casting burial vaults in separable upper and lower sections, although it 15 is to be understood that the device could well be used for other purposes for which it is applicable.

The principal object of the invention is to provide a single mold which may be 20 employed to equal advantage in casting both the upper and lower sections of the vault.

A further object is to provide novel means for securing a plurality of extension plates to the sides and ends of the molding frame 25 so that the size of the mold may be varied.

Yet another object is to provide a mold of the class described, which although being simple and inexpensive will be highly efficient and durable.

30 With the foregoing general objects in view, the invention resides in the novel features of construction and unique combinations of parts to be hereinafter fully described and claimed, the descriptive matter 35 being supplemented by the accompanying drawings which form a part of this specification and in which:

Figure 1 is a top plan view of the improved mold showing the same assembled 40 for casting the bottom section of a vault;

Fig. 2 is a longitudinal section of Fig. 1 on the plane of the line 2—2;

Fig. 3 is a vertical transverse section on the plane indicated by the line 3—3 of 45 Fig. 2;

Fig. 4 is a top plan view of the mold assembled for casting the upper section of a vault;

Fig. 5 is a longitudinal section of Fig. 4 50 on the plane of the line 5—5 thereof;

Fig. 6 is a vertical transverse section on the plane indicated by the line 6—6 of Fig. 5;

Fig. 7 is a perspective view of one corner

of the frame assembled as shown in Figs. 55 1 and 2;

Fig. 8 is a similar view with the parts arranged as depicted in Figs. 4 and 5;

Fig. 9 is a detail top plan view showing one of the extension plates in use; 60

Fig. 10 is a side elevation of said plate;

Fig. 11 is a vertical section of Fig. 10 on the plane of the line 11—11 thereof;

Fig. 12 is a top plan view of the extension plate shown in Figs. 9, 10 and 11; and 65

Fig. 13 is a vertical transverse section through a portion of a vault constructed in the improved mold.

In the drawings above briefly described, the numerals 1 and 2 designate respectively 70 the inner and outer molding frames between which the vault is cast. The frame 1 includes side member 3 and end member 4, said members being preferably, but not necessarily formed of boards. All of the members 3 and 4 are shouldered at their ends as indicated at 5, said ends abutting corner posts 6, said posts being preferably formed of metal although wood or any other suitable material could well be used. The side 75 members 3 and 4 will in most cases be secured to the corner posts 6 by means of suitable angle metal brackets such as those indicated at 7. It will be understood, however, that any other suitable means could well be 80 employed for this purpose. 85

Secured to the outer faces of the side and end members 3 and 4 respectively are strips of molding 8, said strips extending along the upper edges of said members and being 90 provided on their outer faces with longitudinal ribs 9. The ends of the strips of molding 8, abut right angular corner members 10 which are secured by screws or the like 11 to the upper ends of the corner posts 95 6, said corner members having ribs 12 which align with the ribs 9 of the strips 8. The construction just described, forms an internal seat or shoulder 13 at the upper edge of the lower section of the completed vault 100 as will be clear from Figs. 3 and 13, said seat having a longitudinal groove 14 which is formed by the ribs 9 and 12. The seat 13 receives therein the upper section 15 of the vault which section, in addition to the lower 105 section, is formed by the improved mold.

The outer frame 2, includes side and end members 16 and 17 respectively, which are

preferably constructed of boards although metal construction could well be employed should occasion demand. As shown clearly in several figures of the drawings the end members 17 are shiftable longitudinally of the side members 16 and may be held in adjusted position by transverse bolts 18 which are receivable in openings 19 formed through said members 16. By this detail of construction the length of the outer frame may be varied for casting vaults of different lengths, the length of the inner frame 1 being also variable, by means yet to be described.

As shown in the drawings the side members 16 are constructed of two boards 20 and 21 secured together, one edge of the boards 20 being removed as shown at 22 so that an external enlargement will be formed at the upper edge of the vault, it being in this enlargement that the seat 13 is located as will be clear by reference to Figs. 3 and 13. The outer faces of the side members 16, at the edge thereof remote from the cut-away portion of the board 20, are provided with longitudinal ribs 23 which are adapted to form grooves 24 in the outer side of the upper vault section 15 as shown clearly in Figs. 6 and 13, it being necessary, however, to invert or reverse the side and end members 16 and 17 respectively, when the upper section is to be constructed.

The end members 17 are shown as constructed of outer and inner boards 25 and 26, one edge portion of the former having a longitudinal rib 23' corresponding to the rib 23 whereas the opposite edge of the other board is cut away at 22'. The object of this construction is the same as the corresponding construction of the side members 16 and need not be further explained. It may be set forth, however, that since the ends of the members 17 abut the boards 20, it is necessary to provide filling blocks 27 between said end members and the boards 21 when casting the lower section of the vault. The use of the filler blocks 27 is not necessary, however, when molding the upper section of the vault, as the end members 17 then come in tight contact with the boards 21 of the side members 16 as shown most clearly in Fig. 8, said end members being grooved at their extremities for the reception of the rib 23.

When molding the lower part of the vault or the like, the device will rest on a horizontal pallet 28 as depicted in Figs. 1, 2, and 3. When, however, the upper section of the vault is being cast, a depressed pallet 29 will be employed as will be clear from Figs. 4, 5 and 6, it being then necessary to provide a pair of curved filler strips 30 between the lower edges of the end members 4 and the pallet 29. See more particularly Fig. 6. The pallet 29 will in most cases be provided with means for holding rings or other suitable handles 31 so that the latter will be

inset or molded in the top of the upper vault section. This construction is also illustrated more particularly in Fig. 6, although it is shown also in Fig. 5.

Since the vertical relation of the inner and outer frame 1 and 2 respectively, remains the same when casting either the upper or the lower section of the vault, any preferred means may be employed for supporting the former from the latter. For illustrative purposes, I have shown transverse angle iron bars 32 secured to the frame 1 and having projecting ends which overlie the outer frame 2. This construction is simple and inexpensive yet produces the required result. It may also be said that although any adequate means may be employed for suitably spacing the side members of the inner frame 1, transverse angle iron bars 33 are preferably provided for this purpose, the ends of said bars being supported by suitable brackets 34 which project inwardly from the frame as shown most clearly in Figs. 1, 2, 3 and 6.

I have stated above that extension plates 35 are provided for increasing the dimensions of the inner molding frame 1. These plates are featured in Figs. 9, 10, 11 and 12, in which figures they are identified by the reference numeral 35. The plates 35 are suitably shouldered at their edges for proper engagement with the corner posts 6 and the side and end members 3 and 4 respectively, said plates having transverse dove-tail grooves 37 which align with similar grooves 38 formed in said side and end members, said aligned grooves receiving therein dove-tail dowel pins 39 which may be anchored by any preferred means such as the screws 40 shown in the drawing. As will be clear from Fig. 9, proper insertion of the plates 35 will increase the length of the inner frame 1. Whenever it is desired to increase the width of this frame, however, it is necessary also to vary the length of the end members 17 of the outer frame 2. This may be done in any preferred manner, as by substituting longer end members or inserting suitable extension plates or the like between the extremities of said members and the side members 16. It may be stated, however, that in most cases, it is not necessary to vary the width of the molding frame, but only the length thereof, the width remaining the same for vaults of numerous sizes.

When constructing the lower section of the vault, the frame is set up as shown in Figs. 1, 2, 3 and 7, the boards 20 and 26 being then positioned inwardly so that they will form the external enlargement on the vault for the seat 13. With the parts assembled in this manner, the green cement or the like is poured in the space between the inner and outer frames and is troweled over the pallet 28. It will thus be seen that

the strips of molding 8 will form the seat 13 and the grooves 14 thereof. After the cement has set the required amount, the inner frame is dis-assembled and removed, 5 after which it is re-assembled upon the curved pallet 29, the filler strips 30 being interposed between the end members of said frame and said pallet as depicted in Fig. 6. When the outer mold is removed from the 10 previously cast lower section of the vault, the side and end members thereof are inverted and at the same time, what were previously their outer faces are disposed inwardly. The entire mold now stands as 15 shown in Figs. 4, 5 and 6, so that when the green cement is poured into the space between the inner and outer frames, the top section of the vault will be constructed, the ribs 23 serving to form an additional groove 20 in said top section for registration with the grooves 14 of the lower section as shown in Fig. 13. The inner or upper section of the vault is sufficiently small to permit a slight space to exist between said upper section and 25 the seat 13, this space being filled with cement or the like after the casket has been placed in the vault. This forms an effective seal, as will be obvious, although it is to be understood that the present invention resides 30 in the molds and not in the vaults completed thereby.

I attach great importance to the fact that the side and end members of the outer frame are reversible for casting both the upper and 35 lower sections of the vault. By this construction, only one molding apparatus is necessary for the manufacture of the entire vault, this meaning a great saving. Furthermore, the undertaker or other person who 40 constructs the vault, is not encumbered with a multiplicity of differently constructed molds to be carried around from place to place as occasion may demand. I also wish to emphasize the simple and inexpensive 45 construction of the entire device and to di-

rect attention to the fact that regardless of this extreme simplicity, the invention will be highly efficient and durable.

From the foregoing, taken in connection with the accompanying drawings, the construction, manner of operation and advantages of the improved mold will be readily understood without requiring further explanation. It may be stated, however, that within the scope of the invention as claimed, 55 numerous minor changes may be made without sacrificing the principal advantages.

I claim:

1. In a vault mold, the combination of inner and outer molding frames between 60 which both the bottom and the top sections of the vault are cast, the sides of one frame having its opposite faces of different shapes for molding the top and bottom sections, respectively, both sides being reversible to 65 bring either face into operative position.

2. In a vault mold, the combination of an inner molding frame, strips of molding and means for detachably securing them to the upper edge of said frame on the outer face 70 thereof, an outer frame having on its outer side a bead near one of its edges, the inner side of said outer frame being cut away along its opposite edge, and means for securing the sides and ends of said outer 75 frame detachably together to permit them to be inverted.

3. A mold including a molding frame, extension plates for increasing the dimensions of said frame, said plates and frame having 80 aligned dove-tail grooves, and dove-tail dowel pins received in said grooves.

In testimony whereof I have hereunto set my hand in the presence of two subscribing witnesses.

CARL W. BAUMGARDNER.
